L. C. LARSEN,
MOLD FOR SURFACING PILES.
APPLICATION FILED AUG. 19, 1918.

UNITED STATES PATENT OFFICE.

LARS C. LARSEN, OF SAN FRANCISCO, CALIFORNIA.

MOLD FOR SURFACING PILES.

1,283,222.

Specification of Letters Patent. Patented Oct. 29, 1918.

Application filed August 19, 1918. Serial No. 251,040.

To all whom it may concern:

Be it known that I, LARS C. LARSEN, a citizen of the United States, residing in the city and county of San Francisco, State of California, have invented a new and useful Improvement in Molds for Surfacing Piles, of which the following is a specification.

My invention relates to improvements in forms for surfacing piles and the like where-
10 in semicircular sections operate in conjunc-
tion to form an annular channel around the
pile to be surfaced; and the objects of my
invention are:

First, to provide an improved form for
15 surfacing partially submerged piles and the
like;

Second, to provide an improved device of
the character described adapted to be easily
20 and readily placed around and removed
from the pile to be surfaced.

Third, to provide an improved mold
adapted to retain a grouting element in po-
sition until properly set.

I accomplish these several objects by
25 means of the device disclosed in the draw-
ings forming a part of the present specifica-
tion wherein like characters of reference are
used to designate similar parts throughout
30 the said specification and drawings, and in
which—

Figure 1 is a partly broken elevation of
my improved form in position around a pile
to be surfaced;

Fig. 2 is a broken view disclosing in ele-
35 vation the upper portion of a form and the
manner in which the sections thereof are de-
tachably secured together;

Fig. 3 is a plan view of Fig. 2; and

Fig. 4 is a bottom view of Fig. 1.

40 Where piles are partially submerged it
is sometimes desired to surface said piles
with a coating of cement or the like to pro-
tect their surfaces from the attacks of tor-
pedoos and other marine insects.

45 I accomplish this coating of surfacing
after the piles are in position readily plac-
ing and removing the sections of which the
mold is formed without injury to the pile.

50 Referring to the drawings the numeral 1
is used to designate in general a form com-
prising vertically disposed cylindrical sec-
tions 2 open at the ends thereof and provided
at each end with semicircular bands or
55 hoops 3. Each end of each hoop or band 3
is provided with a notched lateral extension
4 which extensions lie adjacent to each other

when the sections 2 are assembled into a
complete form 1.

A suitable latch 6 rests within the notches
of the extensions 4 and is provided with a 60
beveled recess 7 to engage and thereby re-
tain the lateral extensions 4 and the sec-
tions 2 together.

By reason of the beveled or chamfered
nature of the recess 7 of the latch the said 65
latch may be easily removed to separate the
sections 2.

The lower ends of each section 2 are each
provided with a semicircular beveled flange
8 the adjoining flanges 8 of adjacent sec-
70 tions 2 operating to form a continuous in-
ternal annular flange, the purpose of which
will hereinafter be more fully set forth.

The upper end of each section 2 is pro-
vided with a series of wedges 9 which op-
erate in conjunction with separable wedges
10 and blocks 11 set against a pile 12, or
other thing to be surfaced, to center the
75 form 1 relatively to the said pile 12 whereby
an annular channel may be provided be-
tween the interior surfaces of the sections 2
and the exterior surface of the pile 12 or the
like.

Each section 2 is also provided with an
aperture 14, as disclosed in Fig. 1 of the 85
drawings, and closable by means of a suit-
able plug 16.

In operation the device is as follows:

The completed form 1 consisting of the
sections 2 is assembled around the pile 12 or 90
the like by matching or registering the
lateral extensions 4 of the bands or hoops
3 as disclosed in Figs. 2 and 3 of the draw-
ings. The latches 6 are then inserted within
95 the notches of the lateral extensions 4 to
rigidly secure the sections 2 together.

Blocks 11 are placed against the pile 12
near the top of the sections 2 and the top
of said sections, or the completed form 1,
are centered with said pile 12 by driving 100
in wedges 10 between the wedges 9 on the
sections 2 and the blocks 11 against said
pile 12, as disclosed in Figs. 1 and 3 of the
drawings.

I prefer to employ a sufficient number of 105
wedges to retain an annular channel of uni-
form width around the entire periphery of
the pile 12 to be surfaced.

When placed in position the lower ends
of the sections 2 are preferably placed be-
110 low the low water line as disclosed in Fig.
1 of the drawings.

A grouting element consisting of a suitable fabric 17 filled with a mixture of proper proportions of sand and cement, 18 is placed within the sections 2 and upon the semicircular flanges 8 in the bottom thereof.

This grouting element is tamped or otherwise operated to center the lower portion of the sections 2 with the adjacent portion of the pile 12.

10. A second layer of sand and cement 18 of the requisite depth or amount is then placed in position and the plugs 16 are removed from the apertures 14 in the sections 2 to admit water above the grouting thereby 15 equalizing the hydrostatic pressure above and below the grouting to prevent the pressure of water from below from displacing the grouting until it is set and sufficiently hard to serve as a support for the surfacing 20 to be applied later.

After the grouting element has set the plugs 16 are reinserted within the holes 14 and the water pumped from the interior channel between the pile 12 and the interior 25 of the form 1. A surfacing mixture of concrete or cement is then poured into the mold to fill the channel and after said surfacing mixture has hardened or set the sections 2 are easily and readily removed by detaching 30 the latches 6, removing the wedges 10 and blocks 11, and then separating and removing the sections 2 from the hardened surface.

By removing the grouting support or flange 8 from the bottom of the sections 2 it 35 is evident that said sections may be superimposed one upon the other to build up a surface of any desired length or height.

Having thus described my invention what I claim as new and desire to secure by Letters Patent is—

40. 1. A surfacing mold for piles and the like comprising matched semicircular sections; means for centering one end of the matched molds relatively to a pile; and means for 45 supporting a grouting element at the other ends of the matched sections.

2. A surfacing mold for piles and the like comprising vertically disposed semicircular

sections; means for centering the upper ends of the sections relatively to a pile; means 50 for supporting a grouting element at the lower ends of the sections and around the pile to be surfaced; and means for equalizing a hydrostatic pressure above and below a grouting placed upon the supporting 55 means to retain said grouting in position.

3. A surfacing mold for piles and the like comprising vertically disposed semicircular sections; means for centering the upper ends of the sections to a pile; means 60 for supporting a grouting element at the lower ends of the sections and around the pile to be surfaced; means for equalizing a hydrostatic pressure above and below a grouting placed upon the supporting means 65 to retain said grouting in position; and means for detachably retaining the sections together.

4. A surfacing mold for piles and the like comprising a pair of matched, vertically 70 disposed semicircular sections; means for detachably securing the sections together; suitable wedges for centering the upper ends of the sections relatively to a pile to be surfaced; a semicircular beveled flange secured 75 within the lower end of each section to support a grouting element around the pile; and means for equalizing hydrostatic pressure above and below the grouting.

5. A surfacing mold for piles and the like 80 comprising a pair of vertically disposed semicircular sections having apertures therein to permit the passage of water when said molds are submerged; semicircular hoops secured to the molds and having notched adjacent ends; suitable latches arranged to engage the ends of the hoops and thereby detachably retain the sections together; suitable wedges arranged to center the top of the sections relatively to the pile to be 85 surfaced; and a semicircular beveled flange secured within the bottom of each mold to support a grouting element around the pile.

In witness whereof I hereunto set my signature.

LARS C. LARSEN.
